CLAIM

The ornamental design for a battery holder, as shown and described.

DESCRIPTION

FIG. 1 is a perspective view of a battery holder showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 in FIG. 6;

FIG. 9 is a cross-sectional view taken along line 9-9 in FIG. 6;

FIG. 10 is a cross-sectional view taken along line 10-10 in FIG. 6;

FIG. 11 is an enlarged view of the portion, labeled '11' in FIG. 1;

FIG. 12 is a perspective view thereof, shown with additional broken line subject matter.

FIG. 13 is a front view thereof, shown with additional broken line subject matter;

FIG. 14 is a cross-sectional view taken along line 14-14 in FIG. 13;

FIG. 15 is a cross-sectional view taken along line 15-15 in FIG. 13; and,

FIG. 16 is a cross-sectional view taken along line 16-16 in FIG. 13.

The dashed broken lines illustrate portions of the article that form no part of the claimed design. The dot-dash broken lines represent the boundaries of the claimed design, and form no part thereof. The dashed broken lines showing a battery in FIGS. 12-16 are for the purpose of illustrating environmental structure, and form no part of the claimed design. The dot-dot-dash broken lines illustrate a portion of

(Continued)

the article that is enlarged for clarity of illustration and form no part of the claimed design.
